Bayard C. Dickinson, Abington Township,
Montgomery County, Pa.

Application January 5, 1954, Serial No. 28,377

Term of patent 14 years

(Cl. D80—1)

To all whom it may concern:

Be it known that I, Bayard C. Dickinson, a citizen of the United States, residing at 1837 Canterbury Road, Abington Township, Montgomery County, Pennsylvania, have invented a new, original, and ornamental Design for Display Device, of which the following is a specification: reference being had to the accompanying drawing, in which:

Fig. 1 is a perspective view of a display device, showing my new design;

Fig. 2 is a front elevational view showing the design;

Fig. 3 is a side elevational view of the design; and

Fig. 4 is a rear elevational view of the design.
I claim:

The ornamental design for a display device, substantially as shown.
